UNITED STATES PATENT OFFICE.

FRANK McINTYRE, OF BROOKLYN, ASSIGNOR TO THE EAGLE PENCIL COMPANY, OF NEW YORK, N. Y.

DESIGN FOR A LEAD-PENCIL.

SPECIFICATION forming part of Design No. 23,211, dated April 24, 1894.

Application filed March 22, 1894. Serial No. 504,728. Term of patent 14 years.

To all whom it may concern:

Be it known that I, FRANK McINTYRE, of Brooklyn, in Kings county and State of New York, have invented a new and original Design for Lead-Pencils, of which the following is a specification, reference being had to the accompanying drawings, in which—

Figure 1 is a perspective view, and Fig. 2 is a cross section enlarged of a lead pencil embodying the design.

Under my invention the exterior surface of the pencil sheath which incloses the lead is subdivided into figures *a* of parallelogram shape, between which intervene sunken lines

b extending spirally around the sheath, and *c* intersecting sunken straight lines *c* extending lengthwise of the sheath.

What I claim, and desire to secure by Letters Patent, is—

The design for a lead pencil as herein shown and described.

In testimony whereof I have hereunto set my hand, before two subscribing witnesses, this 20th day of March, 1894.

FRANK McINTYRE.
